UNITED STATES PATENT OFFICE.

ALANSON P. BRUSH, OF DETROIT, MICHIGAN, AND WALTER C. BAKER, OF LAKEWOOD,
OHIO.

BRAKE.

1,034,579.

Specification of Letters Patent.

Patented Aug. 6, 1912.

Application filed September 17, 1908. Serial No. 453,421.

To all whom it may concern:

Be it known that we, ALANSON P. BRUSH, a citizen of the United States, residing at Detroit, in the county of Wayne and State 5 of Michigan, and WALTER C. BAKER, a citizen of the United States, residing at Lakewood, in the county of Cuyahoga and State of Ohio, have invented a certain new and useful Improvement in Brakes, of which the 10 following is a full, clear, and exact description.

The object of the present invention is to provide an improved form of brake which shall have certain advantages of construction and operation not possessed by such devices of this class as have been heretofore known to the art.

The invention more particularly is directed to a form of band brake especially adapted for use on automobiles and similar vehicles and comprises features of construction which render it not only strong and easy to assemble, but enable it to operate with equal efficiency for either direction of rotation.

A particular embodiment of our invention is described in the following specification with reference to the accompanying drawings in which:

Figure 1 is a side elevation of our brake 30 device attached to the fixed or dead axle of an automobile, the axle being shown in cross-section in the drawing. Fig. 2 is a top plan view of the same and Fig. 3 is a detail section showing the relation of the ends of the 35 brake band to the mounting.

In the construction which we have here shown, the brake comprises a drum A rigidly connected with the vehicle wheel, the drum being of the conventional cup shape 40 and having a cylindrical flange A' with a friction surface upon the exterior. Mounted upon the fixed axle B aforesaid and rigid therewith, is a bracket C which has secured thereto a closing plate C' for said drum.

Projecting from the bracket are extensions 45 C², C³ having sockets for a pair of studs C⁴, C⁵, having flanged ends which project laterally across the face of the drum but are spaced apart therefrom so as to allow the 50 brake band D to pass beneath them. These studs are also spaced apart from each other so as to allow the ends of the brake band and the ears or projections D', D², secured to the said ends, to lie within the space be-

tween the studs and have a slight range or 55 movement there between. An operating crank arm E forming one part of a toggle is pivotally secured to the projection upon one end of the brake band, while a link E' 60 pivotally mounted at the elbow of the crank arm and pivotally secured to the bracket upon the other end of the brake, forms the other part of the toggle.

Retaining hooks C⁶, C⁷, secured near the 65 edge of the closing plate of the drum extend laterally across the face of the drum and serve to retain the brake band against sidewise displacement. It will thus be seen that the brake band floats loosely within the field fixed by the two studs C⁴, C⁵ having 70 flanged ends and the retaining hooks C⁶, C⁷ just described, but that it may be closed upon any movement of the crank arm which 75 operates the toggle to draw the ends of the band together.

Upon the drawing of the brake band down upon the drum the latter will, of course, by reason of the frictional contact, immediately drag the brake band forward, 80 in the direction of its rotation, and the forward ear or projection—that is, the ear or projection lying in advance in the direction of rotation, will immediately catch 85 against the stud adjacent thereto and be held thereby while the rotating drum will tend to drag the other loose end of the band forward and thus wind it more tightly upon the drum and increase the braking effect. It is to be noted that with the construction 90 which we have devised, it is absolutely immaterial in which direction the rotation takes place. Thus the ends of the brake band will be perfectly free ordinarily, or when not in use, and yet be so disposed that either end thereof, dependent upon the direction of rotation of the drum, will become automatically fixed as soon as the brake is put into use, with the result that the brake 95 is equally efficient no matter whether the vehicle be running forward or backward.

It will be observed that the power-applying mechanism, consisting of lever and toggle link pivotally connected to each other and to the ends of the brake band, is floating, in the sense that it requires no other 105 guide or support than its connections with the brake band with which it floats as occasion demands.

Having thus described our invention, we claim:

1. A brake comprising a drum, a floating brake band lying adjacent to the drum and free from fixed attachment at either end, ears at the ends of the band having oppositely disposed shoulders, a fixed member of the frame in axial alinement with the drum, a bracket rigidly attached to said member and having transverse pins adapted to engage the shoulders on the brake band, retaining hooks fixedly supported, extending outside of and across the band but unattached thereto, said hooks being adapted to retain the band in proper relation to the drum, substantially as described.
2. A brake comprising a drum, a floating brake band lying adjacent to the drum and having free ends, oppositely disposed

shoulders on the ends of the band, a fixed member of the frame in axial alinement with the drum, a bracket rigidly attached to said member and having transverse pins adapted to engage the shoulders on the brake band, a cover plate connected to the bracket, retaining hooks secured to said cover plate and embracing the band but unattached thereto, with means for applying the band to the drum, substantially as described.

In testimony whereof, we hereunto affix our signatures in the presence of two witnesses.

ALANSON P. BRUSH.
WALTER C. BAKER.
